VARIABLE COMPRESSION SYSTEM FOR
INTERNAL COMBUSTION ENGINES

John P. Gaty, New York, N. Y.

Application March 1, 1933, Serial No. 659,058

16 Claims. (Cl. 123—48)

In the development of this art, various efforts have been made from time-to-time to overcome the inherently low efficiency of internal combustion engines at part loads, by different forms of 5 variable compression ratio devices, which, theoretically would maintain substantially constant compression pressures at the completion of the compression stroke, regardless of the load factor of the engine. In the earliest developments, these 10 devices were manually operable. Later, automatic means were proposed to effect the adjustments necessary. All such devices however, so far as known, were lacking in mechanical simplicity and practicability from the manufacturing and servicing points of view.

In the prior designs referred to, pistons were used as displacement means. These however, are impractical for two main reasons. Such pistons do not move except during periods when engine loads are changing, which introduces lubrication difficulties and blow-by of gases cannot be prevented. The other reason referred to is that of the increased cost of manufacture and maintenance. The latter can be appreciated from the 20 fact that usually an overhead crankshaft has been provided connecting all the displacement pistons, involving greatly increased cost and additions in weight and dimensions of the engine.

The objects of the present invention may be 25 stated as being broadly to overcome such prior objections and to provide simple, efficient and satisfactory means for automatically adapting the compression ratio to the existing needs of the engine.

Accordingly, the present invention differs from 30 previous proposals, in that accurate compensation for load changes is effected by varying the total displacement of a group of displacement devices in a multi-cylinder engine without endeavoring specifically to adjust each displacement 35 device to the same quantitative change. Thus load changes on the engine are accompanied by accurately controlled changes in the clearance volume of the entire engine without individual 40 control over changes in individual cylinders otherwise than by the mean effective pressure existent in such cylinders at the particular time considered. The result of this is that a cylinder having 45 weak compression due to leaking piston rings or valves, will receive more compensation than other cylinders having tight valves and piston rings, the torque effort being thus smoothed out and the performance of the engine improved. This particular novel feature renders unnecessary 50 the present close control of combustion chamber

volumes in the cylinder head, machining operations that are very expensive due to the irregular shape of the clearance space, difficulty of measuring the volume, etc.

Thus, one of the main features of the invention 5 is this control of the total compensating volume of the system of displacement devices in accordance with the load upon the entire engine and the compensation of each cylinder, according to its need as evidenced by a lack of means effective pressure in comparison with the average of the mean effective pressure of the other cylinders.

Other novel features of construction and new 10 combinations and relations of parts constituting the invention will appear as this specification 15 proceeds.

The drawings accompanying and forming part 20 of the specification illustrate certain practical embodiments of the invention, but it is to be understood that the structure may be modified and changed, all within the true intent and broad scope of the claims:

Fig. 1 is a diagrammatic representation of the 25 system.

Fig. 2 is a broken sectional view across one of the 30 cylinder heads showing a form of the invention as applied to a so-called L-head type engine.

Fig. 3 is a similar view of the invention as applied to a T-head type engine and illustrating the inter-communicating passages between cylinders as cored in the head of the engine.

Fig. 4 is a plan and broken sectional view showing 35 details of the system outlined in Fig. 1.

Fig. 5 is an enlarged broken sectional detail of the instantaneous pressure relief valve for preventing excessive ratio adjustment upon sudden 40 opening of the throttle valve.

Referring first to the diagrammatic layout, Fig. 1, for a general understanding of the invention, 45 it will be noted that the system comprises a main displacement cylinder 1, containing a piston 8, and having a noncompressible fluid, such as a suitable oil at both sides of the same. The back face of the piston forms a movable abutment for chamber 9, to and from which fluid is added or subtracted through valve 10, which is controlled by suitable means in accordance with changing load on the engine.

The rod 11 provides a means for the shifting 50 of piston 8, to adjust and limit the amount of fluid in the chamber 9, in back of the piston and, conversely the amount of fluid in the chamber 12 in front of the piston. The latter communicates by a supply manifold conduit 13 and inlet check valves 14, with the several variable dis-

placement devices 15, and these are in communication with the main supply chamber by return check valves 16 and manifolding 17.

Check valves 14 and 16 prevent fluid flowing in both directions out of the cylinder displacement devices, permitting the fluid to enter only through valves 14 and to leave through valves 16, as indicated by the arrows.

The purpose of this construction as will be observed, is to avoid intercylinder flow of fluid through short pipe lengths between cylinders and to control interchange of fluid by the mean pressure in the cylinders. The resistance to intercylinder flow is dependent upon the length of piping or conduits and the pressure differential between cylinders. The length of time between pressure changes, or the explosion frequency, will govern the amount of fluid transferred from one displacement device to another, the pipe size and length and the pressure differential remaining constant. The construction shown makes it impossible for the fluid to be transferred from one device to another by means of the short paths A, B, between cylinders and requires the travel from A through the variable chamber 12 and around through inlet conduit 13, to the adjoining cylinder at point C. The return conduit 17, may be of larger size than the supply side of the system at 13, to enable the displacement devices to empty rapidly to avoid detonation from excessive pressures in the cylinders. The filling of the displacement devices instantaneously is not so necessary. The inlet side of the system therefore provides the principal force of resistance to intercylinder flow of fluid and the amount transferred from one cylinder to another during a single engine stroke may be of inconsequential volume, even at low operating speeds. Over any reasonably short length of time, the displacement of the device in any particular cylinder will be dependent only upon the relation of the mean effective pressure therein to the mean effective pressure of the other cylinders. The cylinder having the lowest compression receives greater compensation than the other cylinders, tending to increase its work output to approximately normal.

The main displacement piston 8, being backed by non-compressible fluid, it follows that the total displacement of the system is dependent upon the control means and is not subject to momentary fluctuation due to pressure changes during the cycle of operation of the engine. The control means herein provided are such that all conditions of operation can be properly accommodated and compensated for, distinguishing the invention from certain prior systems employing spring loaded displacement means which lack accommodation to sudden increases in load on the engine, due to inertia of the parts or dash pots placed to prevent quick changes and volume fluctuations and the fact that a constant pressure is always maintained against withdrawal of the displacement means from the combustion chamber.

In the control device herein disclosed, a special relief valve is provided to take care of sudden increases in engine load and to allow the cylinder pressure to act against the displacement devices with an opposing pressure, practically equal to atmospheric, instead of a constant pressure of a much higher value, as in the case of spring loaded devices mentioned. This results in more rapid adjustment of the displacement de-

vices to instantaneous increases in load and practically prevents detonation under such conditions. The structure of this special relief valve will be taken up after first considering the actual physical form of the displacement devices.

Reference is now made to Figs. 2 and 3, which show the displacement devices as consisting each of a flexible diaphragm 19, in the cylinder head and forming one wall of the combustion chamber. This diaphragm is illustrated as being carried by a ring 20, seated in the head structure and as carrying a centrally disposed disc 21, cooperating with suitable stop lugs 23, to limit movements in both directions, that is both expansive and contractive movements. For desired flexibility, the diaphragm may be corrugated as at 22, between its rigidly held rim portion and its centrally reinforced disc carrying portion. With this construction, the diaphragm is restrained in its flexing within proper limits, cannot be stressed beyond its elastic limit and the compression ratio may not increase or decrease beyond predetermined limits. When pressure is relieved back of the diaphragm by the control means for sudden load increases, the reinforcing disc may abut some part of the cylinder head such as the front of the stop lugs 23 (Figs. 2 and 3) thus preventing the diaphragm from being stressed, except on the annular mounting ring 20, which is not objectionable as such changes are of short duration.

It will be noted that the backing disc 21 of the diaphragm may be of any desired shape other than the flat form illustrated, such as concave, convex and regular or irregular outline, in accordance with any desired design of combustion space, transfer passages between valve pockets and cylinder bore, etc., and the flexing portion of the diaphragm may be a simple annulus or other desired shape. It is noteworthy, that with this special construction, there is no possibility of gas leakage, the construction cost is low for results accomplished, and the engine is not appreciably increased in physical dimensions or its appearance spoiled.

Other features to be noted by comparison of Figs. 2 and 3, are that the manifolding conduits may be either external piping as in Fig. 2 or internal cored passages in the cylinder head as in Fig. 3 and that the check valves may be either externally or internally located, in the latter instance, being accessible for repair or servicing by means of the removable plugs at 24, 25. Both styles of construction are adaptable to other than L or T-head motors, for example, to the so-called F and J-types of head construction.

To simplify explanation, Fig. 4 may be considered as a top plan view of the engine shown in Fig. 3, combined with the various elements of the control mechanism. In this view, the supply and return piping 13, 17, are shown connected with the chamber 12 of the main displacement cylinder through two-way valves 26, 27, connected together by a link indicated at 28, for simultaneous operation. These valves are provided as a means for enabling the refilling of the cylinder head displacement system, when the head has been replaced after motor servicing operations. In this particular illustration, the valves are indicated in the positions of normal use, that is, with both supply and return pipes 13, 17, directly in communication with the chamber 12 of the main displacement device, the direction of flow being regulated by the check valves as above described and indicated by the arrows, the pipe-

ing 17 being illustrated as actually larger than piping 13, to permit the rapid release of the cylinder head displacement devices as heretofore recited.

One of the principal elements of the control mechanism is a so-called vacuum cylinder 29, connected with the intake manifold of the engine by piping 30 and containing a piston 31, acted on by spring 32 and connected by rod 33, with one end of a floating link 34, whose opposite end is connected at 35, with piston rod 11. When the engine is stopped and atmospheric pressure is present in the upper end of vacuum cylinder 29, spring 32 will force piston 31 downward, air below the piston being relieved through vent 36. As the position of piston 8 is maintained by the non-compressible fluid on both sides of the same, the floating link 34 will swing about the center 35 as a fulcrum. This link has connected with the intermediate portion thereof the rod 37, of the main displacement controlling valve 10. On this valve rod are the two valve elements 38, 39, the first for cooperation with a port 40, opening into the back chamber of cylinder 1, and the second for cooperation with a port 41, for releasing liquid from the cylinder 42, of this valve. In this lowering movement of link 34, as valve member 38 clears the upper edge of port 40, a way for escape of fluid in chamber 9 is opened through such port and the piping 43 to the sump 44. The release of such fluid from the back of the piston 8 enables the spring 45 to lift the piston, which thereby acts to withdraw fluid from the displacement devices in the motor head through conduit 17, into chamber 12. As these displacement devices contract to their minimum displacement positions, no more fluid can flow and consequently piston 8 will come to rest in the course of such movements. The valve 38 has been maintained in the position close to that necessary to close the valve port 40, by reason of the fact that as the vacuum piston 31 moves outward or downward in the illustration, the displacement piston 8 is moving upward, thus in effect compensating the valve displacement and thus holding it in the nearly closed position. Thus when the engine is stopped, the non-compressible fluid is withdrawn from the cylinder displacement devices and the engine is in effect automatically restored to its normal compression ratio which, by way of example, may be on the order of 6 to 1. Therefore, at starting, the engine is in the condition of normal compression ratio. This is particularly an advantage, because it is known that in prior apparatus where springs loaded displacement devices have been used, the starting under abnormally high compression ratios, such as 9 to 1 produced severe detonation, due to full charges in the cylinders and created difficult starting conditions.

Starting, by this apparatus, at the normal compression ratio, the engine may be idled during the usual warming up period, in the course of which, the intake manifold vacuum rises and the pressure differential between the back and front of the vacuum piston 31 increases causing the same to rise approximately as fast as the air can enter through orifice 36. This upward movement of piston rod 33 and the connected end of floating link 34 lifts valve 38, shutting off escape of fluid past the upper edge of the valve and, uncovering the lower edge of valve port 40, permits fluid under pressure from a motor driven pump 46, to pass through piping 47, into the cylinder chamber 9, which acts there to force displacement pis-

ton 8 downward against spring 45, and against the pressure in the displacement diaphragms opposed to the pressure in the engine cylinders. This pressure of the fluid expands the displacement devices, causing them to fill part of the clearance volume in each cylinder, raising the compression ratio and facilitating proper idling, conserving of fuel, etc.

The displacement piston 8 in being forced downward as described, through its piston rod 10 11, carries the connected end of link 34 down with it and, at a time when the maximum desired compression ratio has been attained, the valve port 40 will be closed by the downward movement of valve 38, checking further ratio increasing movement of piston 8. This result can be accomplished by the provision of a stop on vacuum piston 31, such as indicated at 78 for engagement with the lower end of the cylinder, or by the proper regulation of vacuum spring 32. 20 The non-compressible fluid trapped in chamber 9 back to the piston 8 will then prevent any motion of this piston from minor pressure changes in the displacement system, until a change in load on the engine is accompanied by a change 25 in the position of rod 37 of control valve 10.

Assuming by way of further example, that after a proper warming up, increased load is placed on the engine, the consequent reduction in manifold vacuum enables spring 32 to force 30 down piston 31, the connected end of floating link 34 and valve rod 37, causing valve element 38 to open the passage for fluid at the upper edge of port 40, which fluid then flows from the upper chamber 9, port 40 and piping 43 to the sump 44. 35 This relief of pressure fluid permits piston 8 to rise, which withdraws the pressure fluid or liquid from the displacement devices through piping 17, thus reducing the compression ratio with the increase in load on the engine. As soon however as a condition of equilibrium is reached, the rise of piston 8 will lift the floating link 34 to shut off escape of the oil or other pressure fluid past valve element 38 to maintain a sealed system against minor pressure differences in the cylinder head displacement system. 45

With a decrease in engine load and consequent increase in manifold vacuum, the vacuum piston 31 will rise, compressing spring 32, carrying upward the adjacent end of floating link 34 and valve rod 37, permitting liquid under pressure to pass from the pressure source, namely, engine driven pump 46, through the pressure line 47, past the lower edge of valve element 38 and into chamber 9, forcing piston 8 downward and increasing the pressure in the displacement devices, raising the compression ratio accordingly. The piston 8 as it is driven down, carries down with it the fulcrum end of the floating link 34, closing the control valve and thus stopping further movement, as the position of equilibrium is reached.

It will be appreciated from the foregoing, that for any given position of the vacuum piston 31, there will be a corresponding position where displacement piston 8 will come to a state of equilibrium and close control valve 10, stopping further action. The conditions of displacement governed by piston 8 can therefore be controlled by regulation of the vacuum spring 32, and can therefore be regulated according to the degree of vacuum in the intake manifold, which condition therefore can be made to vary inversely as the pressure at the end of the compression stroke. The compression ratio can therefore be corrected by means of this system to take care of 75

variations in the pressure at the end of the compression stroke and thus maintain over a reasonable period of time a constant pressure at the end of the compression stroke whatever the load 5 on the engine.

A special feature of the control valve at 10 is the lower valve head 39, which serves as a balancer to compensate the pressure on the upper valve head 38, enabling the valve rod 37 to float 10 freely and offer very little force in opposition to movement in either direction. From port 41, controlled by the lower valve head 39, by-pass connection 48 leads to the return line 54 to the sump 44. This by-passes the pressure fluid from pipe 47, when port 41 is uncovered by lowering valve head 39, when low manifold vacuum occurs, as under fully open throttle valve operation. In such case, the liquid pressure is not required and hence, while chamber 9 is emptying through port 40 and piping 43, the pressure is also being relieved from the valve cylinder through by-pass port 41 and connections 48, 54. Such relief of pressure takes the load from the pump and conserves work of the engine. A drain 49 extends 20 from the bottom of the valve cylinder and is connected with the by-pass preventing trapping of liquid beneath the balancing piston valve 39. In some cases, the oil pump provided as a standard part of the engine may be used to supply pressure through the piping 47 and in such instances, the by-pass 41 for relieving the pressure is not required nor desirable since the oil pressure should be maintained for the moving parts of the engine.

An additional special feature of the invention 35 is the mechanism for instantaneously relieving chamber 9 of pressure when the load on the engine is suddenly increased. This mechanism overcomes inherent delayed action of the vacuum cylinder and floating link mechanism, or such 40 other control means as may be provided. If the throttle valve is suddenly opened to its full extent from a nearly closed position, the pressure rise in the engine cylinder is extremely rapid and compensation by the entire mechanism would require a measurable space of time. Because of such lag, the instantaneous pressure relief device indicated at 50, in Fig. 4, is provided and this is coupled by linkage 51, with the throttle valve or accelerator mechanism indicated in a 45 general way at 52. Briefly, this pressure release device serves to by-pass liquid from chamber 9, through piping 53, 54, to the sump 44, when the throttle valve is suddenly opened, automatically emptying chamber 9 sufficiently to compensate 50 for the increase in total clearance volume required by the engine to maintain approximately constant compression ratio. As chamber 9 is emptied, vacuum piston 31 is then rapidly lowered under action of spring 32, then no longer 55 counteracted by high manifold vacuum.

For complete understanding of the sudden throttle opening instantaneous pressure release, reference is to be had to Fig. 5, which illustrates the internal features of this mechanism. The 60 piping 53 extending from the chamber 9, above the displacement piston is of larger diameter than supply piping 47, Fig. 4, and hence capable of draining this chamber more rapidly than it can be filled through such supply pipe. Similarly, 65 all parts and connections are of relatively high capacity. Chamber 55, Fig. 5, into which pipe 53 opens, is subjected to the same pressure as chamber 9 and consequently, the relief of pressure in one is accompanied by relief of pressure 70 in the other. When the throttle valve is sud-

denly opened and link 51 is drawn to the left, the lever 56, actuated thereby, forces plunger 57, toward the right and this through spring 58, shifts the surrounding plunger 59, but in accordance with certain pressure conditions. The secondary 5 plunger 59, has a stepped portion 60, forming a piston operating through a partition 61, separating the two chambers 62, 63, as piston 60 is moved into chamber 63, it causes a displacement of fluid from chamber 63 to 62, the rapidity of flow of fluid 10 from chamber 63 into chamber 62 is governed by the restricted orifice 64 in the separating wall 61. The restriction of orifice 64 causes an increase in fluid pressure in chamber 63 and a decrease in chamber 62. The differential pressure 15 thus produced acts upon the opposed faces of the stepped piston 60 to resist its motion, and this resisting force may be greater than the force necessary to compress the spring 58, thus allowing plunger 57 to move within the outer plunger 59. 20 In the relative movement of the two plungers thus effected by the delayed action of the outer piston plunger, the ports 65, in the tubular portion of the inner plunger 57 will come into register with the ports 66, in the surrounding sleeve portion 25 of the outer plunger, to permit fluid to pass from chamber 55, through the tubular portion 67, of the inside plunger to chamber 68, and thence to the sump by piping 54. Hence, any sudden opening of the throttle valve automatically results in 30 the release of pressure from in back of the piston in the main displacement cylinder and resultant reduction of the compression ratio, as heretofore described.

Slower opening of the throttle valve permits 35 time for transfer of liquid from chamber 63, into chamber 62, through orifice 64, enabling spring 58, to carry the stepped plunger along with the directly actuated plunger, the two then travelling along together without registering the valve ports 40 65, 66, so that no liquid will be released and necessary changes in displacement volume will then be effected automatically as before described in connection with Fig. 4.

The mechanism described will function at all 45 times, no matter how suddenly the load on the engine may vary. The plunger 57, is held at all times in engagement with the throttle actuated lever 56, by spring 69, Fig. 5, and this sleeve of plunger 57 carries a stop shoulder 70, to engage 50 the end of the surrounding plunger sleeve. Consequently, sudden closure of the throttle through spring 68 and shoulder 70, will cause the plunger 57, to shift to the left and to carry along with it the outer plunger 59. In this instance, the piston 55 portion 60, of the outer plunger offers no resistance to the follow-up motion, because of the presence of a relatively large spring closed valve 71, in partition 61, which permits free transfer 60 of liquid from chamber 62, into chamber 63.

An opening 72 permits chamber 62 to be kept filled from chamber 55. No change in the volume of the system through motion of plunger 59 occurs however, unless ports 65, 66, are brought into registry. This prevents the imposition of 65 any pressure effects on the throttle valve mechanism that might not be desirable.

The sudden pressure release mechanism being connected in the main pressure system, it follows 70 that any change of viscosity in the pressure liquid acts to compensate the reaction of plunger 59, for changes in the rest of the system. Thus, an increase in viscosity of the fluid in the system, which might cause sluggishness in compensation 75 also causes greater resistance to motion of plunger 75

er 59, at medium velocities of movement, and therefore will produce valving under less rapid changes in throttle operation, so that the device is in effect self-compensating. A line 76, extending from chamber 71 back to the sump 44, provides for drainage of liquid, which may leak past the plungers 57, 59, back to the sump.

The invention does not interfere with the usual engine servicing operations. When the cylinder head of the engine is to be removed, it is only necessary to disconnect the two lines 13 and 17 at the head. When this is done, the liquid in the displacement devices may be drained and saved. After the head is replaced and the piping again connected, the valves 26 and 27, are turned counter clock-wise in Fig. 4, so as to disconnect the supply and return pipes 13, 17, from displacement cylinder 1, and to connect them respectively, through said valves by piping 13, 47 with the pump and piping 74 with the sump 44. This puts the pump directly across the displacement devices, enabling the pump, when the engine is started, to entirely fill the cylinder head system and to drive out all air. To prevent any trapping of air in this portion of the system, the displacement devices may be made with sloping roof portions 75, Figs. 2 and 3, to permit all air to pass out during this refilling operation. When the system has been completely filled with liquid in this manner, the valves 26, 27, may be returned to the normal operating position. It will be seen from this that the invention presents no additional service problems.

The invention, it will be noted, provides a complete, practical system, readily applicable to existing engines of standard types, and operable to automatically adjust the compression ratio in accordance with changing engine loads, while permitting desirable compensation for individual cylinders and automatically prevents excessive or undesirably high compression settings at starting or on sudden increased loading by throttle operation. The diaphragms can be sufficiently flexible to effect the necessary changes in clearance volume, being backed up by incompressible fluid which carries the actual pressure load and being protected against excessive expansion or contraction by the stop means limiting movements of the same. The system also adds no appreciable bulk to the engine, is not expensive, not liable to get out of order and introduces no complications in the way of ordinary service operations about the engine.

What is claimed is:

1. A variable compression system for multi-cylinder internal combustion engines, comprising in combination with cylinders of a multi-cylinder internal combustion engine, liquid volume operated compression ratio adjusting displacement devices for the individual cylinders, liquid connections between the same including liquid volume displacement means for positively varying the total clearance volume of the several cylinders and intercylinder flow control means for compensating the individual cylinders to controlled flow of displacement liquid between the displacement devices of the several cylinders.

2. A variable compression system for multi-cylinder internal combustion engines, comprising in combination with cylinders of a multi-cylinder internal combustion engine, liquid volume operated compression ratio adjusting displacement devices for the individual cylinders, liquid connections between the same including liquid vol-

ume displacement means for positively varying the total clearance volume of the several cylinders, intercylinder flow control means for compensating the individual cylinders to controlled flow of displacement liquid between the displacement devices of the several cylinders, said latter means consisting of flow throttling means in the connections aforesaid.

3. Variable compression means for multicylinder combustion engines, comprising in combination with the cylinders of a multicylinder combustion engine, independently operable liquid actuated clearance volume adjusting displacement devices for the several cylinders of the engine, integrating clearance volume adjusting mechanism connected with said displacement devices, means for effecting control of said integrating clearance volume adjusting mechanism and flow regulating control means enabling individual adjustment of the displacement devices of the several cylinders of the engine.

4. A variable compression system for multi-cylinder internal combustion engines, comprising in combination with the cylinders of a multi-cylinder internal combustion engine, liquid actuated displacement devices for the individual cylinders of the engine, an integrating clearance volume determining device and connections between the latter and the individual displacement devices including means enabling self-adjustment of the cylinder displacement devices independently of each other, but subject to the general control of the integrating clearance volume adjusting device.

5. A variable compression system for multi-cylinder internal combustion engines, comprising in combination with the cylinders of a multi-cylinder internal combustion engine, liquid actuated displacement devices for the individual cylinders of the engine, an integrating clearance volume determining device, connections between the latter and the individual displacement devices including means enabling self-adjustment of the cylinder displacement devices independently of each other, but subject to the general control of the integrating clearance volume adjusting device and engine controlled means for setting said integrating clearance volume determining device, said device including a piston for varying the volume of liquid back of all the displacement devices for the individual cylinders and the engine controlled means having an operating connection with said piston.

6. In combination, a multicylinder internal combustion engine, liquid actuated displacement devices in the cylinders of said engine, an integrating clearance volume determining device and supply and return conduit connections from said latter device to said displacement devices and one of said conduits being restricted as compared with the other to enable compensation as between the displacement devices of the individual cylinders.

7. In combination with a multicylinder internal combustion engine, clearance volume controlling diaphragms sealed in the heads of the individual cylinders, liquid supply and return conduits in communication with the displacement diaphragms of the different cylinders, an integrating clearance volume determining displacement device and engine controlled mechanism governing operation of said integrating clearance volume determining device.

8. In combination with a multicylinder internal

- combustion engine having a throttle valve governing operation of the same, clearance volume controlling diaphragms sealed in the heads of the individual cylinders, liquid supply and return conduits in communication with the displacement diaphragms of the different cylinders, an integrating clearance volume determining displacement device in communication with said supply and return conduits and means controlled by adjustment of said throttle valve for operating said integrating clearance volume determining device. 5
9. In combination with an internal combustion multicylinder engine, a fluid actuated displacement device in each cylinder of the same, means for supplying non-compressible fluid to each of said displacement devices and means for effecting displacement of all air from the supply of non-compressible fluid to the displacement device including connections providing a circuit for temporary circulation of non-compressible fluid through all the several displacement devices and an air separating chamber in said connections. 10
10. In combination, an internal combustion engine, a liquid actuated displacement device in the cylinder of the same, a pressure liquid supply system connected with said displacement device and including a variable displacement chamber consisting of cylinder and a piston therein, a valve controlling liquid pressure for operating said piston, a second cylinder and piston subjected to manifold pressure of the engine and a floating link connection between said pistons and said valve. 15
11. A multicylinder internal combustion engine having intake manifold and throttle valve mechanism, liquid pressure actuated displacement devices in the cylinders of said engine, a main displacement device and liquid pressure connection from the same to said cylinder displacement devices and a quick acting pressure relief device actuatable by said throttle valve mechanism and comprising valving means automatically operable to vent liquid pressure from said main displacement device upon sudden 20
- 45 throttle valve opening movements. 25
12. A multicylinder internal combustion engine having intake manifold and throttle valve mechanism, liquid pressure actuated displacement devices in the cylinders of said engine, a main displacement device and liquid pressure connection from the same to said cylinder displacement devices, a quick acting pressure relief device actuatable by said throttle valve mechanism and comprising valving means automatically operable to vent liquid pressure from said main displacement device upon sudden throttle valve opening movements and a vacuum cylinder and piston connected with the intake manifold and operable 30
- to control the main displacement device on less sudden movements of the operation of the throttle valve. 35
13. In combination, a multicylinder internal combustion engine, clearance volume determining diaphragms sealed in the heads of the individual cylinders of said engine, means for supplying non-compressible fluid in back of said diaphragms, means for releasing non-compressible fluid from in back of the diaphragms, said release means operating faster than said supply means and means common to both said supply means and to said release means for arbitrarily governing the total volume of all the non-compressible fluid in back of the diaphragms. 40
14. In combination, a multicylinder internal combustion engine, pressure actuated displacement devices in the individual cylinders of said engine, liquid supply and return manifolds connected with said displacement devices of the individual cylinders, a variable liquid supply source common to both supply and return manifolds, one way valves opening from the return manifold to the displacement devices of the individual cylinders and one way valves opening from the displacement devices of the individual cylinders to the return manifold. 45
15. In combination, a multicylinder internal combustion engine, pressure actuated displacement devices in the individual cylinders of said engine, liquid supply and return manifolds connected with said displacement devices of the individual cylinders, a variable liquid supply source common to both supply and return manifolds, one way valves opening from the return manifold to the displacement devices of the individual cylinders, one way valves opening from the displacement devices of the individual cylinders to the return manifold, said return manifold being larger than the supply manifold to rapidly release 50 the displacement liquid from the cylinder displacement devices and means connected with said return manifold for suddenly relieving pressure therein. 55
16. In combination, a multicylinder internal combustion engine, clearance volume determining diaphragms sealed in the individual cylinders of said engine, means for supplying and for releasing non-compressible fluid to and from in back of said diaphragms and including a variable non-compressible fluid supply source common to the diaphragms of all the several cylinders of the engine and means for varying the same to determine the total volume of the non-compressible fluid in back of the diaphragms of all the cylinders of the engine. 60
